(57) **CLAIM**

The ornamental design for a lid for packaging as shown and described.

DESCRIPTION

1. Lid for packaging

1.1 : Perspective

1.2 : Back

1.3 : Left

1.4 : Front

1.5: Right

1.6:Top

1.7: Bottom

The present design relates to a lid for packaging for foodstuff as illustrated in the annexed drawings, in which: FIG. 1.1 is a perspective view of the present design; FIG. 1.2 is a back view thereof; FIG. 1.3 is a left view thereof; FIG. 1.4 is a front view thereof; FIG. 1.5 is a right view thereof; FIG. 1.6 is a top view thereof; and FIG. 1.7 is a bottom view thereof.

(Continued)

The broken lines are shown for the purpose of illustrating parts of the article that form no part of the claimed design.
